UNITED STATES PATENT OFFICE.

HARRY M. SALYER, OF NEWARK, NEW JERSEY, ASSIGNOR TO AMERICAN PERFORATED MUSIC CO., A CORPORATION OF NEW YORK.

APPARATUS FOR PERFORATING MASTER MUSIC-SHEETS.

No. 918,375.

Specification of Letters Patent.

Patented April 13, 1909.

Application filed June 15, 1907. Serial No. 379,144.

To all whom it may concern:

Be it known that I, HARRY M. SALYER, a citizen of the United States, and resident of Newark, in the county of Essex and State 5 of New Jersey, have invented certain new and useful Improvements in Apparatus for Perforating Master Music-Sheets, of which the following is a specification.

The object of my invention is to provide 10 improved means for perforating sheets of paper or other suitable material for use in musical instruments commonly called "automatic pianos", "piano players", and the like, and my invention comprises the novel 15 details of improvement and combinations of parts that will be more fully hereinafter set forth and then pointed out in the claims.

Reference is to be had to the accompanying drawings forming part hereof wherein, 20 Figure 1 is a side elevation of an apparatus embodying my invention, the key-board being removed, Fig. 2 is a partly broken plan view showing a portion of the key-board in position, Fig. 3 is an end view of 25 the machine, partly broken, looking from the right in Fig. 1, the key-board being removed. Fig. 4 is an enlarged vertical section of the sheet-punching device, Fig. 5 is a section on the line 5, 5, in Fig. 4, looking 30 in the direction of the arrows, Fig. 6 is a vertical section, enlarged, through the punch operating devices, Fig. 7 is a detail perspective view of the punch controlling device, Fig. 8 is a similar view of part of 35 the device for controlling the punch for producing rows of perforations near the edges of the sheet, Fig. 9 is a detail sectional view illustrating the manual key-controlling device of a circuit for a punch, and Fig. 10 is 40 a diagrammatic view illustrating an arrangement of circuits and magnets controlled by the manual keys.

Similar characters of reference indicate 45 corresponding parts in the several views.

The numeral 1 indicates a suitable frame or casing provided with a takeup roll or drum 2 carried by a shaft 3 suitably journaled in frame 1. Roll 2 is shown provided 50 near its opposite ends with a series of pins 4 suitably spaced apart to enter perforations 5 near opposite edges of the sheet 6 to be perforated, whereby said pins may pull the sheet over a suitable plate 7 from a supply reel. Roll 2 is to be rotated step by 55 step to advance the sheet 6 as hereinafter

explained. The sheet 6 before reaching roll 2 passes across the guide 8, that is supported by and extends across frame 1, and which is provided with a suitable series of holes 8^a that respectively receive the punches 9, which are shown extending in a straight line, guide 8 being shown provided with a lower series of holes 8^b for the punches, for freely guiding said punches to have vertical movement (see Figs. 4 and 6). The sheet 6 also passes under a die 10 secured upon frame 1 over guide 8 with a sufficient space between them for the passage of sheet 6, said die being provided with holes 10^a aligned with holes 8^a for the passage of punches 9 through said holes and the sheet for perforating the latter. The upper part of die 10 is shown troughlike at 10^b to receive the punched out pieces from sheet 6.

To cause the punches 9 to perforate the 75 sheets 6 as required I provide the following arrangement:—Each punch 9 has a projection or pin 11 adapted to rest upon a flange 12 shown supported beneath guide 8, and said pins slide in guiding grooves 13 vertically disposed in a bar 14 extending across the frame beneath guide 8, whereby the punches may slide freely and are kept from rotating. Beneath the punches 9 is a reciprocative head 15 extending across the frame 80 and suitably guided at its ends, which head 15 is shown pivotally connected by a suitable link or turn-buckle 16 with an eccentric 17 on drive shaft 18 that is journaled in frame 1 and shown provided with a pulley 19 receiving a belt 20 from a suitable motor or other driving device 21, whereby said head may be reciprocated at the desired speed 85 continuously during operation. Head 15 is provided with a series of horizontally disposed slots or guides 15^a (Fig. 4) which may be provided between lugs 15^b formed on the upper edge of head 15 and corresponding lugs 22^a depending from a plate or bar 22 secured over head 15. Plate 22 has holes 22^b 100 receiving punches 9 and engages pins 11 to pull the punches from sheet 6 as head 15 descends. The slots or guides 15^a of head 15 receive slides 23 located beneath and in the plane of punches 9 but normally held retracted from beneath said punches, and arranged to be moved or pushed forwardly beneath the punches according to the perforations desired to be made in sheet 6. To limit the motion of slides 23 in opposite 105 110

directions I provide a bar 24 secured to and extending along head 15 and entering recesses 23^a in the under sides of slides 23.

To control the slides 23 at will, I provide devices connected with electro magnets whose circuits are controlled by manual keys as follows:—To each slide 23 is pivotally connected a link 25 which is pivotally connected at its outer end to a bell-crank lever 26 pivotally supported upon a cross bar 27 extending across frame 1, and the outer arms of said levers 26 are connected by rods 28 with armatures 29^a of electro magnets 29, springs 30 connected with bars 27 and acting upon levers 26 serving normally to push said levers back to withdraw slides 23 from under the corresponding punches 9 and move the armatures from the magnets. The levers 26 are shown made of flat metal twisted at their outer ends and having holes receiving rods 28, nuts 28^a on said rods adjustably connecting them with said levers. For convenience of assembling and locating the parts there may be any desired number of bars 27 carrying levers 26 suitably disposed thereon to permit all the links 25 to extend forwardly to their corresponding slides 23. The series of magnets 29 (one for each lever 26) may be suitably disposed upon shelves 30 or supports 31 carried by frame 1, the location of magnets 29 and levers 26 being such as to most suitably locate the parts in operating relation. The manual keys 32, 33, which may be arranged on a key-board A at one side of frame 1, in manner similar to the manual keys in a piano action, are each adapted to make and break the circuit of a different magnet 29, and for this purpose the wires 34 from the different magnets lead to corresponding contacts 35 beneath the keys, adapted to be engaged by a contact 36 carried on the under side of each key (see Figs. 9 and 10), and for convenience of wiring I have shown the companion contacts 37 respectively connected with conductors 38, 39 which respectively connect by conductors 40, 41 with ground conductors 42, 43 to which the different series of magnets on the shelves 31 connect as by conductors 44 (Fig. 10), a generator 45 and suitable switch 46 being included in the circuit. The two conductors 42, 43 are shown connected by conductor 47 (Fig. 1). Conductor 38 and the associate contacts 35, 37 lie under the series of keys 32 and connect with appropriate magnets 29, while conductor 39 and the associate contacts 35, 37 under keys 33 connect with other appropriate magnets 29. The magnets are shown mounted upon two shelves for convenience in locating the parts and to economize space, and the rods 28 from the lower series of magnets pass through openings 31^a in the shelf above them. When any key is depressed its contacts 35, 36, 37 will close the circuit of the corresponding magnet whose

armature upon being attracted will cause its lever 26 to push the corresponding slide 23 beneath the corresponding punch 9, and when the key is released the circuit will be broken and spring 30 will cause the slide to be withdrawn from under the punch.

The two slides 23^b at the extreme ends of the series of punches are designed to punch the series of holes 5 near the edges of sheet 6, and are therefore not controlled by magnets but are normally held pushed forward under their respective punches 9 by springs 28^a suitably connected with frame 1 and acting upon bell-crank levers 26^a connected by links 25^a with said punches, which levers are pivotally carried upon cross bar 27 (see Figs. 1 and 8). The slides 23^b are pushed back to prevent operation of their punches at certain times and in accordance with the distance desired between the perforations 5 of music sheet 6.

To cause the required travel of sheet 6 over punches 9 and to control the operation of the punches through the music sheet I provide the following arrangement: At 50 is a ratchet wheel journaled upon frame 1, as upon a pivot or stud 51, and to said wheel is connected a pinion 52 that meshes with a gear 53 secured on shaft 3, and at 54 is a dog to actuate said ratchet and carried by a slide rod 55 guided in suitable bearings 56 of frame 1 and carrying a spring 54^a acting upon dog 54 to normally move said dog toward ratchet 50. A spring 55^a connecting rod 55 with frame 1 tends to normally keep said rod elevated and take up slack in the joints. At 57 is a lever or arm, shown in the form of a bell-crank, pivotally supported upon frame 1, as at 58, and having its upper end bearing against dog 54 and normally held toward said dog, as by a spring 59 of greater tension than spring 54^a, and the opposite arm of said lever is connected by a rod or link 60 with a suitable pedal 61 to be controlled by the foot of the operator. Rod 55 is to be reciprocated by shaft 18, and for this purpose is pivotally connected by a pitman 62 with a crank pin 63 on said shaft. When the parts are in the normal position shown in Fig. 1 and shaft 18 revolves, the head 15, rod 55 and dog 54 will reciprocate without operating ratchet 50, but when the pedal is depressed arm 57 will swing back from engagement with dog 54 and permit said dog to engage ratchet 50 to thereby cause rotation of roll or drum 2 in the direction of the arrow a, to feed music sheet 6 forward. As it is not required that the perforations 5 at the edges of sheet 6 be so near together as the music perforations 6^a of said sheet may be, the endmost slides 23^b are held back from beneath their respective punches at certain times, and for this purpose I provide upon the roll or drum 2 at one end a toothed or notched wheel or disk 130

64 against which a finger 65 is adapted to act, said finger being shown carried by a rock shaft 66 extending across frame 1 adjacent roll 2. Said shaft also carries arms or 5 fingers 67 whose upper ends are in line with the slides 23^b and bear against the same respectively. When finger 65 enters a notch in disk or wheel 64 the slides 23^b will be pushed forwardly by their springs 28^a under the corresponding punches 9 and then upon the next rise of head 15 holes 5 will be punched in sheet 6 near opposite edges, but when the surface portion 64^a engages finger 65 the latter will be pushed back and through 10 its shaft 66 will cause the fingers 67 to push slides 23^b back from under their punches until another notch of disk 64 aligns with the end of finger 65, when said slides will again move forwardly to cause their punches 15 to punch holes 5 in sheet 6. To hold slides 23^b pushed back from under their respective punches at will, I have shown an arm 68 secured on shaft 66 adapted to be engaged by a lever or arm 69 pivoted upon frame 1, as 20 at 70, suitable means, such as a frictional device or expanding spring 71, being provided to hold the arm 69 in set position. In the position shown in Fig. 6 the finger 65 and slides 23^b will be free to operate, but when 25 arm 69 is moved forwardly at the top to push arm 68 to the left in Fig. 6 finger 65 will be kept from engagement with disk 64 and slides 23^b will be pushed back from under their punches and held retracted. By 30 this means suitable adjustment of sheet 6 may be made while head 65 continues to reciprocate without perforating the sheet. A shaft 72 journaled in frame 1 between guide 8 and roll 2 guides sheet 6 to the latter, 35 Said shaft is eccentrically supported as by eccentric screws or studs 72^a, and may be held in set position by screw 72^b. By shifting the position of shaft 72 the length of sheet 6 between punches 9 and pins 4 on roll 40 2 may be regulated so that holes 5 of sheet 6 will properly engage said pins, it being understood that the number of holes 5 in sheet 6 between punches 9 and pins 4 must be a multiple of the distance between pins 4. 45 It is designed that the operator may determine the number of perforations 6^a to be made in the sheet at any time by assistance of an audible signal produced at each feeding stroke of dog 54, and for this purpose 50 I provide a spring finger 73 adapted to engage ratchet 50 and shown carried by a shaft 74 supported in a bearing 75 carried upon the key-board framing A and held rigid by a screw 75^a carried by bearing 75, a finger 55 76 on shaft 75 permitting convenient turning of shaft 74 for adjusting the tension of finger 73 against ratchet 50. By this means each time that ratchet 50 is turned a step the click of finger 73 from tooth to tooth of 60 the ratchet will produce an audible signal 65 which the operator will note in counting the time for holding one or more of the manual keys depressed and for causing dog 54 to reciprocate.

77 indicates a shield below roll 2 to guard sheet 6 as it drops from roll 2.

The operation of perforating the music sheet in accordance with my improvements may be described as follows: The sheet being laid over plate 7 passes between guide 75^a and die 10, over shaft 72, and upon roll or drum 2 and holes 5 of the sheet are engaged with the pins 4, and then the sheet is in position to be perforated. Shaft 18 having been started, the operator then places his finger upon the desired key or keys 32, 33, whereupon circuit of the corresponding magnet or magnets will be closed at 35, 36, 37 and their corresponding armatures will be drawn down and through the 85 respective levers 26 and links 25 the corresponding slides 23 will be pushed forward under the corresponding punches 9, head 15 and rod 55 will reciprocate but sheet 6 will not advance. To advance sheet 6 and to 90 cause the punches to punch the desired number of holes 6^a while the fingers remain upon the keys, pedal 61 is depressed which causes the upper end of arm 57 to move back from dog 54 and thereupon said dog engages ratchet 50, and for each downward stroke of the dog said ratchet is turned the distance of one tooth which causes roll or drum 2 to advance correspondingly and by its pins 4 engaging holes 5 pulls the music sheet 6 100 under die 10, said sheet stepping definite and equal distances, and the operator counts by the audible sound from the sounder the number of operating strokes required of dog 54, and when the operator has counted 105 the desired number of strokes of the punches he releases the treadle, and arm 57 withdraws dog 54 from ratchet 50 which then becomes inoperative while head 15 and dog 54 continue to reciprocate, and during such 110 time the operator, by removing one or more fingers from the keys, may break the circuit of the corresponding magnet or magnets to cause the corresponding slide or slides 23 and punches 9 to become inoperative while 115 the other slides continue to push up their punches, according to the character and number of perforations required as the measure or time of the musical composition may require. The operator will again select 120 and hold down the required keys, operate the pedal to cause the desired number of punch holes to be made, and then release the pedal, and so on according to the perforations required in the music sheet. During 125 such operation the required holes 5 in the sheet will be punched each time that finger 65 drops into a notch in disk 64, and the relation of the parts may be such that the holes 5 will be punched a distance corresponding 130

to five consecutive perforations 6* in sheet 6, or in other desired definite number as to the latter perforations. The relation of eccentric 17 to crank pin 63 is such that dog 54 will not operatively engage a tooth of ratchet 50 on the down stroke until head 15 has pulled the punches 9 down through sheet 6, whereupon dog 54 on the continued down stroke will move the ratchet 50 a space of one tooth and no more until the next down stroke so that the sheet 6 will not be fed forwardly while the punches engage the same.

For producing spaces in sheet 6 appropriate to the musical notation of the composition, the operator will not depress the manual keys while the pedal is depressed to cause dog 54 and ratchet 50 to turn roll 2 to advance the sheet the required distance.

Having now described my invention what I claim is:

1. An apparatus for perforating music sheets, comprising a reciprocative head, a plurality of punches independent thereof, means for continuously reciprocating said head, means for guiding the punches, a die for said punches, manual keys, devices to co-act with said punches respectively and each controlled independently by a key and normally out of operative relation with their respective punches, a takeup roll provided with pins for a perforated sheet, means for rotating said roll step by step after the punches have receded from said sheet, means for punching holes in the sheet near the edge simultaneously with perforating the sheet, and means controlled by said roll for operating the last named punching means.

2. An apparatus for perforating music sheets, comprising a reciprocative head, a plurality of punches independent thereof, means for guiding the punches, a die for said punches, manual keys, devices to co-act with said punches respectively and each controlled independently by a key and normally out of operative relation with their respective punches, a takeup roll provided with pins for a perforated sheet, means for rotating said roll step by step after the punches have receded from said sheet, said head having slides near opposite ends adapted to co-act with corresponding punches to punch series of holes near the sides of the sheet, and means for retracting said slides from said punches and simultaneously operating said roll at definite periods.

3. An apparatus for perforating music sheets, comprising a reciprocative head, a plurality of punches independent thereof, means for guiding the punches, a die for said punches, manual keys, devices to co-act with said punches respectively and each controlled independently by a key and normally

out of operative relation with their respective punches, a takeup roll for a perforated sheet, means for rotating said roll step by step after the punches have receded from said sheet, said head having slides near opposite ends adapted to co-act with corresponding punches to punch series of holes near the sides of the sheet, arms opposed to said slides, a finger connected with said arms, and means connected with said roll to co-act with said finger to retract said slides from their punches at definite periods.

4. An apparatus for perforating music sheets, comprising a reciprocative head, a series of punches independent thereof, manual keys, devices to co-act with said punches respectively and each controlled independently by a key and normally out of operative relation with their respective punches, a takeup roll for a sheet, means to operate said roll step by step after the punches have receded from the sheet, said head having slides near opposite ends to co-act with punches near opposite ends of the series of punches, springs connected with said slides and normally pushing them under the corresponding punches, and means for periodically retracting said slides from under their punches to cause the latter to produce rows of perforations in the sheet near its edges at definite distances apart.

5. An apparatus for perforating music sheets, comprising a reciprocative head, means for continuously reciprocating the same, a series of punches independent of said head, means for guiding the punches, a die for said punches, manual keys, devices to co-act with said punches respectively and each controlled independently by a key, a takeup roll for a sheet, a ratchet connected with said roll to rotate the latter, a continually reciprocative dog to act with said ratchet, means to hold said dog normally out of engagement with said ratchet, and means to cause said dog to engage said ratchet at will to operate the roll step by step.

6. An apparatus for perforating music sheets, comprising a reciprocative head, means for continuously reciprocating the same, a series of punches independent of said head, means for guiding the punches, a die for said punches, manual keys, devices to co-act with said punches respectively and each controlled independently by a key, a takeup roll for a sheet, a ratchet connected with said roll to rotate the latter, a reciprocative rod operatively connected with said head to reciprocate coincidently continuously therewith, a dog carried by said rod to engage said ratchet and normally disengaged therefrom, means to hold said dog out of engagement with said ratchet, and means to at will cause said dog to engage

said ratchet for rotating said roll step by step.

7. An apparatus for perforating music sheets, comprising a reciprocating head, means for continuously reciprocating the same, a series of punches independent of said head, means for guiding the punches, a die for said punches, manual keys, devices to co-act with said punches respectively and each controlled independently by a key, a takeup roll for a sheet, a ratchet connected with said roll to rotate the latter, a reciprocative rod operatively connected with said head to reciprocate coincidently continuously therewith, a dog carried by said rod to engage said ratchet and normally disengaged therefrom, means to hold said dog out of engagement with said ratchet, and means to at will cause said dog to engage

said ratchet for rotating said roll step by step, the relation of said dog to said head being such that the dog will not move the ratchet until the punches are retracted from the sheet.

25 8. An apparatus for perforating music sheets, comprising a reciprocative head, means for continuously reciprocating the same, a series of punches independent of said head, means for guiding the punches, a die for said punches, manual keys, devices to co-act with said punches respectively and each controlled independently by a key, a takeup roll for a sheet, a ratchet connected with said roll to rotate the latter, a reciprocative rod, means for operating the same coincidently continuously with said head, a dog carried by said rod to engage said ratchet, a lever carried by the frame engaging the dog to normally hold it disengaged from the ratchet, a pedal connected with said lever, and means for causing said dog to engage the ratchet when released by said lever.

9. An apparatus for perforating music sheets comprising a reciprocative head, a series of punches independent thereof, means for guiding the punches, a die for said punches, means for at will operating any

of said punches, a takeup roll having pins, means for operating said roll step by step, a toothed disk connected with said roll, a finger to engage said disk, and arms connected with said finger to control punches near opposite ends of the series of punches to punch definitely spaced holes in the sheet to receive the pins on the takeup roll.

10. An apparatus for perforating music sheets comprising a reciprocative head, a series of punches independent thereof, means for guiding the punches, a die for said punches, means for at will operating any of said punches, a takeup roll provided with equally spaced pins, means for operating said roll step by step, a toothed disk connected with said roll, a finger to engage said disk, and arms connected with said finger to control punches near opposite ends of the series of punches to punch definitely spaced holes in a sheet to receive the pins on said roll, and means for holding said finger out of engagement with said disk at will to prevent operation of the punches controlled by said finger.

11. An apparatus for perforating music sheets comprising a reciprocative head, a series of punches independent thereof, means for guiding the punches, a die for said punches, means for at will operating any of said punches, a takeup roll, means for operating said roll step by step independent of the operation of the head, a toothed disk connected with said roll, a finger to engage said disk, and arms connected with said finger to control punches near opposite ends of the series of punches, an arm connected with said finger, a lever to co-act with said arm to hold said arm retracted from the toothed disk, and means for holding said lever in set position.

Signed at New York city, in the county of New York and State of New York this 10th day of June A. D. 1907.

HARRY M. SALYER.
